UNITARY SELF-ADJUSTING HANDLE

Filed April 20, 1948

FIG. 1.

FIG. 2.

FIG. 3.

INVENTOR.
ALFRED J. HAYDEN,

BY
McMorris, Berman & Davidson
ATTORNEYS.

metal, such as steel or the like, and may have any finish desired, and it is obviously simple in form and therefore cheap to manufacture.

In order to release the handle, it is a simple procedure to swing the outer end upwardly and thus release the hook 10 from rim 11 of the can when it will come free and may be suspended by aperture 7 upon a hook or nail until required again.

Obviously, the handle may be made of different sizes so that not only the range of cans mentioned may be handled thereby, but larger sizes may also be used, and I am, therefore, not limited to any particular size of handle nor range of sizes of cans that may be handled by means of this invention.

Manifestly, variations may be resorted to and parts and features may be modified or used without others within the scope of the appended claims.

Having now fully described my invention, I claim:

1. In a sheet material can handle, an elongated handle portion terminating at one end in a lateral return bent hook, a portion of said handle portion intermediate its ends being cut out to provide

an abutment portion, said abutment portion projecting at an acute angle from the plane of the handle portion at the same side of the handle portion as said hook and toward said hook.

2. In a sheet material can handle, an elongated handle portion terminating at one end in a lateral return bent hook, a part of said handle portion intermediate its ends being cut out to define a slot and an abutment portion, said abutment portion being directed at an angle from the plane of said handle portion toward and at the same side of the handle portion as said hook from the end of said slot adjacent to said hook.

ALFRED J. HAYDEN.
